EMILE ACHILLE BUTIN AND LOUIS GIRARD, OF LYON, FRANCE.

ARRANGEMENT FOR DIRECTLY REPRODUCING ON FABRIC THE REQUIRED PATTERN.

Application filed August 3, 1925, Serial No. 47,952, and in France August 7, 1924.

This invention relates to warp shedding mechanism for looms of the type employing jacquard needles, each of which is operated by an electric solenoid through contacts moving over a pattern drum having insulating and conducting portions thereon.

The object of this invention is to provide an electrically operated mechanism, which can be applied to existing looms upon the removal of the usual pattern card.

According to one object of the invention, each jacquard needle is operated by a swinging member through a spring loaded sliding rod, the reverse end of which is bent to form a hook to be engaged by a forked lever controlled by the armature of a solenoid when this latter is energized by the circuit being completed through one or more feelers contacting with the pattern painted in conducting material upon an insulating drum or band capable of occupying one of two or three positions.

According to a second object of the invention, the warp shedding mechanism for looms is adapted for weaving patterned velveteens and at this effect, the solenoid circuit is controlled by two needles of unequal length, whose points of contact are separated in the cylinder by the angle rotated at each movement of the pattern drum, the cylinder being capable of occupying one of three positions, the first in which no contact is made, the second in which contact is made with the longer needle, the two positions being occupied alternately on each pick of the shuttle and the third, in which contact with the two needles is made at once and which occurs at the commencement of a section of pattern.

The accompanying drawings show diagrammatically by way of example two arrangements for copying designs for patterned fabrics.

Figure 1 is a diagram of the apparatus constructed in accordance with our invention showing the hook operating mechanism and the pattern cylinder of the design in one position.

Figure 2 is a similar view of the same showing the hook operating mechanism and the pattern cylinder in another position.

Figure 3 is a similar view of the same showing the hook operating mechanism and the pattern cylinder in another position.

Figures 4, 5, 6 and 7 are diagrams illus-

trating the different phases of functioning of this invention.

A member *a* moving on each pick of the shuttle engages a rod *b*. This engagement is made when the member *a* is travelling in the direction of the arrow *c* by compressing the spring *d* which bears on the pusher head *b*¹ on the end of the rod *b* and in the direction of the arrow *c*¹ the engagement takes place directly by the member *a* bearing against a shoulder on the rod *b*.

In its backward and forward movement the rod *b* comes in contact with projections forming stops on a lever *e* pivoted at *e*¹. When the movement is taking place in the direction of the arrow *c*¹ the lever *e* is forced against the electromagnet *f* forming part of an electric circuit hereafter described and remains in contact if a current is flowing, if not it falls away by its own weight.

If the solenoid is energized when the member *a* moving in the direction of the arrow *c*¹ presses the needle *b* against the lever *e*, this latter remains in contact with the solenoid when the member *a* commences to move in the direction of the arrow *c* and the hooked end of this lever *e* prevents the needle *b* from travelling back with the member *a*, the member *a* continuing its movement and compressing the spring *d*. (Fig. 3.) The needle *b*¹ of the hook *b* is therefore not pushed over and a pile thread is brought to the surface.

If, however, the solenoid is not energized the lever *e* falls away therefrom owing to its own weight when the member *a* starts to travel in the direction of the arrow *c* and the needle *b*¹ of the hook *b* is pushed by the needle *b* out of the way of the griffe bar and no pile thread is brought to the surface.

The electric circuit of the solenoid comprises a cylinder *g* of conducting material connected to the frame, and on which is represented the pattern as described hereafter.

Velveteens are generally woven on six staves and therefore after every six picks of the shuttle, and thus after each complete cycle formed in each of two pieces of fabric this cylinder rotates a predetermined amount. It also undergoes a vertical movement at right angles to its axis.

The cylinder *g* is contacted by a double feeler *i* for each jacquard hook *b* the two needles *i*¹, *i*² lying on two different tangents,

set at the angle rotated by the cylinder every six picks, for example, and approximately vertically above the axis g^1 of the cylinder g . Of these two needles one i^1 is longer than the other i^2 .

The double feeler is necessary for weaving velveteens to ensure that parts at the end of a pattern are not missed, and for this purpose two additional picks are inserted, after 10 the feeler i^1 has left the patterned portion of the drum, and this is effected by the feeler i^2 which is still in contact therewith.

One terminal of solenoid f is thus connected to a double feeler i and through it to 15 the machine frame and the other to the second pole of a source of electric supply not shown in the drawings.

The pattern cylinder or drum g is at its highest position as shown in Figure 3, the 20 feeler i^1 being in contact with a conducting or pattern portion g^2 while the feeler i^2 is in contact with insulating portion g^3 , current flows through the magnet f and the lever e is attracted by and held by the magnet and 25 engages and holds the rod b as in Figure 2, allowing the jacquard needle h^1 to be operated upon by the griffe bar and pile threads to be brought to the surface. The pattern drum remains in this position for two picks 30 and then drops to the middle position in which only the feeler i^1 is in contact with the drum but still on a pattern portion g^2 so that current continues to flow while a further four picks are inserted, thus completing 35 six picks of pile for the pattern. The drum then drops to its lowest position in which both feelers i^1, i^2 are out of contact therewith and is rotated through a predetermined angle, to bring the insulating portion into position and again raised to its highest position.

As the weave changes from forming the pattern pile to forming ground work solely the operating mechanism is disposed as follows:

The pattern cylinder or drum g is at its highest position, the feeler i^1 in contact with the insulating portion g^3 but the feeler i^2 is in contact with the pattern portion g^2 , current therefore still flowing through the magnet while a further two picks are inserted. The pattern cylinder, then drops to the middle position, the feeler i^1 remaining in contact with the insulating portion, but the 55 shorter feeler i^2 coming out of contact with the pattern portion, therefore current ceases to flow through the magnet and the pile is not brought to the surface, and a further four picks are inserted. The ground work is 60 then woven without pattern and the pile thread left floating beneath.

The drum again drops to its lowest position in which both feelers i^1, i^2 are out of contact therewith and is rotated through a 65 predetermined angle, being then raised to

its highest position and a further cycle of six picks made.

The ground work is then woven without pattern and the pile thread left floating beneath, the positions of the various operating members being as follows: The drum or cylinder g is in the raised position and the feels i^1, i^2 are in contact with the insulated portion g^3 thereon and no current flows through the solenoid, the pile pattern thread 75 remaining floating beneath the ground work. The cylinder remains in this position for two picks and then moves vertically to the position shown in Figure 1, the feeler i^1 alone remaining in contact with the drum 80 but still on the insulated portion thereof, so that again no current flows through the solenoid. The cylinder remains in this position while a further four picks are inserted. The drum then drops to its lowest position 85 in which both feelers i^1, i^2 are out of contact therewith (as in Figure 2) and is rotated through a predetermined angle, being then raised to its highest position and a further cycle of six picks made.

The invention has been described with reference to a loom for weaving velours but this arrangement may be equally well applied to single fabric looms in this case the feeler is single, the cylinder rotates a suitable amount 90 at each pick of the shuttle and only occupies two positions one high and one low.

What we claim as our invention and desire to protect by Letters Patent is:—

1. Apparatus for tracing patterns for 100 Jacquard looms comprising an oscillating element, a jacquard needle controlling a sliding element arranged for movement corresponding to that of said oscillating element, a pivotally mounted lever having an armature, said lever and said sliding element being provided with means for engagement by said sliding member when the latter is in one position and for release by said sliding member when the latter is in another position, an electric circuit including an electromagnet with which said armature is associated, a circuit closer for said circuit including a contact point, and a movable pattern carrying element provided with a pattern in card form, and an insulating background therefor, said contact point closing said circuit when said pattern comes in contact therewith.

2. Apparatus for tracing patterns for 110 Jacquard looms comprising an oscillating element, a jacquard needle controlling sliding element arranged for movement corresponding to that of said oscillating element, a pivotally mounted lever having an armature, said lever and said sliding element being provided with means for engagement by said sliding member when the latter is in one position and for release by said sliding member when the latter is in another position.

tion, an electric circuit including an electromagnet with which said armature is associated, a circuit closer for said circuit including a pair of spaced contact points of different lengths, and a movable pattern carrying element provided with a pattern in card form, and an insulating background therefor, said contact points closing said circuit when said pattern comes in contact therewith.

3. Apparatus for tracing patterns for Jacquard looms comprising an oscillating element, a jacquard needle controlling sliding element arranged for movement corresponding to that of said oscillating element, and provided at its rear end with a hook arm, a pivotally mounted lever having an armature, said lever being provided with a bifurcated portion in which the hooked end of said sliding element operates for engagement of said lever when said member is in one position and for release of said lever when said member is in another position, an electric circuit including an electromagnet with which said armature is associated, a circuit closer for said circuit including a pair of spaced contact points of different lengths, and a movable pattern carrying element provided with a pattern in card form, and an insulating background therefor, said contact points closing said circuit when said pattern comes in contact therewith.

4. Apparatus for tracing patterns for Jacquard looms comprising an oscillating element, a jacquard needle controlling sliding element arranged for movement corresponding to that of said oscillating element, a pivotally mounted lever having an armature, said lever and said sliding element being provided with means for engagement by said sliding member when the latter is in one position and for release by said sliding member when the latter is in another position, an electric circuit including an electromagnet with which said armature is associated, a circuit closer for said circuit including a pair of spaced contact points of different lengths, and a pattern carrying element provided with a pattern in card form comprising electrically conducting portions and electrically insulated portions, said contact points closing said circuit when said pattern comes in contact therewith.

one position and for release by said sliding member when the latter is in another position, an electric circuit including an electromagnet with which said armature is associated, a circuit closer for said circuit including a pair of spaced contact points of different lengths, and a pattern carrying element provided with a pattern in card form comprising electrically conducting portions and electrically insulated portions, said contact points closing said circuit when said pattern comes in contact therewith.

5. Apparatus for tracing patterns for Jacquard looms comprising an oscillating element, a jacquard needle controlling sliding element arranged for movement corresponding to that of said oscillating element, a pivotally mounted lever having an armature, said lever and said sliding element being provided with means for engagement by said sliding member when the latter is in one position and for release by said sliding member when the latter is in another position, an electric circuit including an electromagnet with which said armature is associated, a circuit closer for said circuit including a pair of spaced contact points of different lengths, and a pattern carrying element provided with a pattern in card form comprising electrically conducting portions and electrically insulated portions, said contact points closing said circuit when said pattern comes in contact therewith, said pattern carrying element comprising a cylinder arranged for step by step rotation and also for movement toward and from said contact points, and the space between said contact points being equal to the angle of each partially rotative movement of said cylinder.
